UNITED STATES PATENT OFFICE

CHARLES D. BOLIN, OF ST. LOUIS, MISSOURI

HEAT REGULATOR

Application filed April 28, 1932. Serial No. 607,930.

My invention relates to oven heat control devices and more particularly to improvements in mechanism for actuating the fuel supply valve.

One of the objects of my invention is to provide a device in which the fuel supply is controlled by a bowed thermally responsive element having its ends interposed between the valve and an abutment spaced from the valve in the direction of the valve movement, whereby increase or decrease in curvature of the element will, through the resultant variation in the distance between its ends, determine the position of the valve with respect to its seat. I prefer to employ as the thermally responsive element, bimetallic strips formed of two metals having different coefficients of expansion. And a further object of my invention is to construct a simple, compact, inexpensive and efficient device embodying this type of valve controlling element.

Other objects will become apparent from the following description of a single embodiment of my invention taken in connection with the accompanying drawing in which Figure 1 is a front elevation of a gas stove, partly in section, showing my improved heat control device installed therein; Figure 2 is a cross sectional view of the fuel valve and the thermo-sensitive control means; Figure 3 is a top view of the thermo-sensitive control means; and Figure 4 is a cross sectional view on the line 4-4 of Figure 2.

Referring to the drawing, the numeral 1 indicates the oven portion and 2 the open burner section of a gas stove. The oven burner 3 receives fuel from the manifold 4 by way of the pipe 5, the thermostatically controlled valve in the casing 8, and the pipe 7. The controlling thermostat extends into the interior of the top of the oven and the pipes 5 and 7 connected with the valve are concealed in the space between the lining and the exterior casing of the oven.

Since the specific type of valve forms no part of my invention, it need only be briefly described. The casing 8 for the valve 12 is provided with a valve seat 9 located between the inlet and outlet chambers 10 and 11. The

outer side of the chamber 11 is formed by cap 13 in threaded engagement with the casing body. A valve setting member 14 extends through the cap and is provided with a slot 15 in its inner end for receiving the flat projection 16 on the disc valve, whereby the valve may be rotated with the setting member 14. A suitable coil spring 17, interposed between the valve 12 and an annular shoulder 18 on the member 14, biases the disc valve toward closed position. The exterior end of the setting member 14 is provided with an indicating plate 19 and a knob 20, the indicating plate cooperating with suitable indicia adjacent an opening 21 in the cap 22 to thereby indicate the temperature of the oven for a particular setting of the valve.

The valve is screw-threaded to a member 23 which is provided with an extension 24 cooperating with a pin 25 whereby the member 23 is prevented from rotation but without interfering with its longitudinal movement on the axis of the valve.

In accordance with the preferred embodiment of my invention I provide the valve casing 8 with an integral extension 26 comprising a block portion 27 adjacent the valve casing and a pair of arms 28 provided with a cross bar 29 at their outer ends. A bearing tube 30 extends through an opening in block portion 27, the opening being in alignment with the axis of the valve. A small rod 31, adapted to have snug sliding fit in the bearing tube 30, abuts the member 23 at one of its ends, the opposite end extending into the space between the arms 28 and being provided with a thermostat engaging member 32. The cross bar 29 of the arms 28 carries an abutment 33 also provided with a thermostat engaging member 34, the member 34 being in axial alignment with the rod 31.

A pair of oppositely bowed thermostatic elements 35 and 36 are interposed between and in abutting engagement with the member 32 and the member 34. Each of the thermostatic elements are formed by fusing or welding two metal strips together, the strips having different coefficients of expansion.

sion, as is well known in the construction of thermostatic elements of this type. The members 32 and 34 are each provided with a pair of notches 37 to receive the ends of the 5 thermostatic elements 35 and 36 and these ends are provided with recesses 38, the bottoms of which cooperate with the bottoms of the notches 37. In order to insure that the thermostatic elements 35 and 36 will not 10 have relative longitudinal movement with respect to the members 32 and 34, when subject to changes in temperature, the surfaces 41 of the bottoms of the notches 37 are formed at right angles to the axis of the rod 15 31. The abutting ends of each of the elements 35 and 36, therefore, will at all times contact the surfaces 41 regardless of the amount of bowing of the elements.

The abutment 33 is connected to the cross 20 bar 29 by a clamping screw 42 extending through slot 43, the abutment 33 being slid- able in groove 44 in the cross bar, thereby providing means by which the abutment can be moved to allow assembly and proper ad- 25 justment of the thermostatic elements 35 and 36 and of the valve opening.

When the oven is cold, the thermostatic 30 elements 35 and 36 will be in their normal bowed position and will maintain the valve in an open position against the action of 35 spring 17, the magnitude of the clearance between the valve and its seat being determined by the dial setting selected. As the temperature of the oven increases, the bi- 40 metallic strips 35 and 36 will be bowed out- wardly toward the arms 28 due to the differ- ence in the coefficients of expansion of the metals forming each strip, the strips being so formed that the metal on their concave 45 sides has lower expansion coefficient than that on their convex sides. This bowing outwardly of the strips decreases the dis- tance between the ends of each strip, thereby permitting the spring 17 to move the valve toward closed position. When the temper- 50 ature of the oven has reached the value indicated by the indicating plate, the opening of the valve will be such as to allow sufficient fuel to pass to the burner 3 to maintain this temperature.

It will be noted that my improved ther- 55 mostatic valve operating mechanism em- bodies no pivots or "lost motion" between parts and, therefore, the accuracy of its tem- perature control in accordance with dial settings, is not subject to being disturbed by 60 shocks to the stove or to the portion pro- jecting within the oven through contact with the cooking utensils inserted therein, and, 65 also, that the use of bowed thermostatic strips in endwise relation to the valve oper- ating rod permits the over-all length of the control device to be much shorter than that of devices in which the valve opening is con- trolled by differences in linear expansion

of elements. It will be understood that a single bowed thermostatic element could be used, but the use of two such elements in the manner herein described, greatly improves the operation and sensitivity of the device in 70 that thinner thermostatic strips may be em- ployed without producing the condition that the thermostatic device may be distorted to the slightest degree by the pressure of the spring 17. 75

Having fully described my invention, what I claim as new and desire to secure by Letters Patent of the United States is:

1. In apparatus of the class described, the combination of a valve biased to closed po- 80 sition, an abutment spaced from said valve in the direction of its closing movement, and temperature responsive means comprising an element which bends under the in- fluence of temperature changes and thereby 85 varies the distance between its ends, one of said ends engaging said abutment and the other forming a stop for the valve.

2. In apparatus of the class described, the combination of a valve, a slidable member 90 cooperating with said valve, an abutment spaced from said slidable member, a bowed thermally responsive member interposed be- 95 tween and having one end bearing on the abutment and the other end being on the slidable member, said valve, slidable mem- 100 ber, and the ends of said bowed member all being in longitudinal alignment, and a spring biasing the valve toward closed posi- 105 tion and maintaining the ends of the bowed member in contact with the slidable member and the abutment.

3. In apparatus of the class described, the combination of a valve, a slidable mem- 110 ber engaging said valve, an abutment spaced from said slidable member, and a bowed thermostatic member interposed between 115 and having its ends in contact with the abutment and the slidable member, the sur- 120 faces on the abutment and the slidable mem- ber which are engaged by the ends of the thermostatic member being at right angles to the axis of the slidable member.

4. A thermo-sensitive unit comprising an abutment, a member movable toward and 115 away from said abutment, and a pair of op- 120 positely bowed elements interposed between the movable member and the abutment, each element having one end engaging the mov- 125 able member and the other end engaging the abutment and each element being com- 130 posed of materials having different coeffi- cients of expansion.

5. A thermo-sensitive unit comprising an axially slidable member, an abutment ax- 125 ially spaced from one end of said member, and a bowed bimetallic element composed of metals having different coefficients of expan- 130 sion, one end of said element bearing on the slidable member and the other end bearing

on the abutment, the surfaces of the slidable member and the abutment which are engaged by the ends of the element being at right angles to the axis of the slidable member.

5 6. A thermo-sensitive unit comprising a movable member provided with a recess at one of its ends, an abutment axially spaced from the recessed end of the movable member and also provided with a recess, and a bowed bimetallic element composed of materials having different coefficients of expansion interposed between the movable member and the abutment and provided with a recess at each end, the recess on the abutment and the movable member being in interengagement with the recess on the adjacent end of the element.

20 7. Oven heat control apparatus comprising a fuel supply valve, means biasing the valve toward closed position, an abutment spaced from the valve in the direction of its closing movement, and thermostatically controlled means for governing said movement, said means comprising a deformable element having an intermediate portion out of alignment with its ends, one of said ends bearing on the abutment member and the other forming a stop maintaining the valve 25 in open position when the oven temperature is below a predetermined minimum.

30 In testimony whereof, I hereunto affix my signature, this 26th day of April, 1932.
